UNITED STATES PATENT OFFICE.

JAMES FRASER, OF EDGEMOOR, DELAWARE, ASSIGNOR TO SPEAKMAN COMPANY, OF WILMINGTON, DELAWARE, A CORPORATION OF DELAWARE.

WASTE FIXTURE.

Application filed August 20, 1923. Serial No. 658,267.

To all whom it may concern:

Be it known that I, JAMES FRASER, a citizen of the United States, and resident of Hillcrest, Edgemoor, in the county of New Castle and State of Delaware, have invented 5 certain new and useful Improvements in Waste Fixtures, of which the following is a specification.

My present invention consists in an improved waste fitting for baths and the like of 10 the type comprising a tubular waste valve the bore of which serves as an overflow passage, and the general object of the invention is to provide a simple and effective fitting of 15 the character specified having provisions whereby a drain pipe may be interchangeably connected to the fitting to extend away from the latter in either of two directions at an angle to one another.

20 The various features of novelty which characterize my invention are pointed out with particularity in the claims annexed to and forming a part of the specification; for a better understanding of the invention however, its advantages and specific objects attained with its use, reference should be had to the accompanying drawings and descriptive matter in which I have illustrated and 25 described a preferred embodiment of my invention.

30 Of the drawings:

Fig. 1 is a sectional elevation of a portion of a bath tub and its fittings;

Fig. 2 is a section through the waste fitting taken similarly to Fig. 1 but on a larger scale; and

Fig. 3 is a section on the line 3—3 of Fig. 2.

40 In the drawings I have illustrated the use of my invention in connection with a bath tub A, having any usual or suitable water supply provisions B, and formed with a waste opening A' at its lower end to which one end of a horizontal waste outlet pipe C is connected in the usual manner. The other end of the pipe C is connected to the inlet D' of my improved waste fitting part D.

50 The fitting part D is in effect a valve casing formed with inlet and outlet chambers D² and D³ separated by an intervening partition D⁴ which is shaped to provide a seat for the lower end of the tubular waste valve E. The valve seat D thus provided is in the form of a vertical cylinder open

at its lower end to the outlet chamber D³, and is laterally cut away so that when the valve is raised, as in the partly open position shown in Fig. 2, the chambers D² and D³ are in direct communication through the 60 cutaway portion of the valve seat. When the valve is in its lower position however, it, in conjunction with the partition D⁴, closes direct communication between the chambers D² and D³, though the bore of 65 the valve E then forms part of an overflow connection communicating with the outlet chamber through the open lower end of the valve, and communicating with the inlet chamber D² through the open upper end of 70 the valve E, and through the annular space between the valve E and a tubular element F, which has its lower end threaded or otherwise secured in an opening D⁵ in the top wall of the casing part D and forming 75 an overflow outlet from the inlet chamber D².

The outlet chamber D³ is provided with two outlet openings, D⁶ and D⁷. The outlet 80 D⁶ leads downward from the bottom of the fitting part D, and the outlet D⁷ leads laterally away from the fitting D usually as shown in alignment with the pipe C. The outlet openings, D⁶ and D⁷, terminate at 85 their outer ends in nipple portions externally threaded and are each formed with a seat for the drain pipe K which may be interchangeably inserted in either nipple, as shown in Figs. 1 and 2. When inserted in either nipple, leakage is prevented by a suitable packing held in place by a gland I threaded on that nipple, while the other outlet opening is then closed by a cap J threaded on the corresponding nipple. As shown the upper end of the valve E is secured to 90 a spider member E' connected by a member G to a valve operating mechanism, shown as comprising a horizontal shaft member H suitably journalled in a slab a, located above the tub A. The shaft H is provided at one 95 end with an operating handle H², and at its opposite end with a crank pin H' in operative arrangement with the upper end of the rod G.

100 With the described arrangement, when the valve member E is in its lower closed position shown in Fig. 1, communication between the inlet port D' and either of the outlet ports D⁶ and D⁷ is closed except for the overflow passage including the bore of 105 110

the valve E and the annular space between it and the tube element F. When the valve member E is raised, as shown in Fig. 2, water entering the fitting D through the inlet D' may pass directly to whichever of the outlets D⁶ and D⁷ is then connected to the drain pipe K.

The described construction is obviously simple and effective for its intended purpose and permits of the interchangeable connection of the pipe K to either of the outlets D⁶ and D⁷, thus making it unnecessary to carry two types of fitting parts D in stock in order to supply the demand for fittings to be used with drain pipe connections leading downwardly and for those leading laterally away from the fitting. The fitting part D readily permits of the machining necessary to insure a proper seating of the valve member E, and to avoid leakage. Advantageously the fitting part D is provided with a lug D⁸, serving as a stop to limit the movement of the valve member E in the closing direction, and preferably the parts are arranged and proportioned, as shown, so that the normal operation of the valve member H will not lift the lower end of the valve member E out of engagement with the upper portion of its cylindrical valve seat.

While in accordance with the provisions of the statutes, I have illustrated and described the best form of embodiment in my invention now known to me, it will be apparent to those skilled in the art that changes may be made in the form of apparatus disclosed without departing from the spirit of my invention as set forth in the appended claims and that in some cases certain features of my invention may be used to advantage without a corresponding use of other features.

Having now described my invention, what I claim as new and desire to secure by Letters Patent, is:

1. A waste valve comprising a chambered casing element having an inlet chamber with an inlet thereto and an outlet chamber with a plurality of outlet openings therefrom and a partition between said chambers shaped to provide a valve seat in the form of a cylinder open at its lower end to said outlet chamber and having a lateral portion cut away, and a tubular valve axially movable in said seat between a lower closed position in which it closes communication between said chambers except for an overflow connection formed in part by the bore of said valve, and an upper open position in which said chambers are in direct communication through said cut away seat.

2. A waste valve comprising a chambered casing element having an inlet chamber with

an inlet thereto, and an outlet chamber with a plurality of outlet openings therefrom, and a partition between said chambers shaped to provide a valve seat in the form of a cylinder open at its lower end to said outlet chamber, and open at its upper end to said inlet chamber and having a lateral portion cut away, and a port in its upper portion substantially coaxial with said valve, a tubular valve member axially movable in said seat between a lower closed position in which it closes communication between said chambers except for an overflow connection formed in part by the bore of said valve, and an upper open position in which said chambers are in direct communication through said cutaway seat, and a tubular element having its lower end connected to said casting in communication with said port and surrounding the upper portion of said valve and separated therefrom by a space forming part of said overflow passage.

3. A waste fitting part in the form of a chambered body having an inlet chamber with an inlet thereto and an outlet chamber and a plurality of outlets therefrom, and a partition between said chambers shaped to provide a cylindrical valve seat open at its lower end to said outlet chamber and also open at its upper end and having a lateral portion cut away whereby a tubular valve seated in said seat closes direct communication between said chambers while its bore forms part of an overflow connection between the chambers and when said valve is lifted, the chambers are in direct communication through the cut away portion of said seat.

4. A waste fitting part in the form of a chamber body having an inlet chamber with an inlet thereto and an outlet chamber and a plurality of outlets therefrom, and a partition between said chambers shaped to provide a cylindrical valve seat open at its lower end to said outlet chamber, and also open at its upper end and having a lateral portion cut away whereby a tubular valve seated in said seat closes direct communication between said chambers while its bore forms part of an overflow connection between the chambers, and when said valve is lifted the chambers are in direct communication through the cut away portion of said seat, said part being also formed with an upper port larger in diameter than, and surrounding said valve seat and communicating with said inlet chamber.

Signed at Wilmington, in the county of New Castle and State of Delaware, this 10th day of August, A. D. 1923.

JAMES FRASER.
